UNITED STATES PATENT OFFICE

OTTO ENGLER, OF KASSEL-WILHELMSHOHE, GERMANY, ASSIGNOR TO SCHMIDT'SCHE HEISSDAMPF-GESELLSCHAFT MIT BESCHRANKTER HAFTUNG, OF KASSEL-WILHELMSHOHE, GERMANY

STEAM GENERATING PLANT INDIRECTLY HEATED BY A CIRCULATING HEAT CARRIER

Application filed July 13, 1931, Serial No. 550,589, and in Germany July 21, 1930.

My invention relates to steam generating plants, in which a circulating heat carrier is utilized for the indirect generation of steam, said steam generating plant having 5 boiler drums which are situated one on a higher level than the other. The object of the invention is to provide a steam generating plant of this kind especially suitable for high output, requiring relatively little space 10 though containing a large heating surface, and having in the boiler drums a large feed space and a high water capacity, to provide for variations in output. For these purposes the water spaces of two drums, being inter- 15 connected, are arranged in such a manner, according to the invention, that only the upper drum has an adjustable water level, while the lower drum is totally or next to totally filled with water. As the water space 20 in the lower drum takes up practically the whole drum it is possible to locate in this water space an exceptionally large heating surface being traversed by the heating medium. Even high fluctuations of the water 25 level occurring in the upper drum will not affect the heating surface in the lower drum. Therefore, with the new boiler, much higher variations of the water level are permissible and the heat storage capacity of the boiler 30 water can be utilized to a much higher extent than with ordinary boilers where each drum has an adjustable water level. The various objects of the invention will be more clearly apparent from a reading of the specification 35 and claims together with the accompanying drawings.

In the drawings an example of the present invention is shown. Fig. 1 is a longitudinal section through the two boiler drums lying one on top of the other. Fig. 2 is a cross section on line II-II and Fig. 3 a cross section on line III-III of Fig. 1.

In the upper drum 1 are located the heating elements 2, in the lower drum the heating elements 4. The heating elements are inserted through the manholes provided on both ends of the drum, the elements lying end to end in pairs. As the lower drum is always practically filled with water, a very large heating surface can be located in this drum.

In the example illustrated this is shown by arranging three heating elements 4 side by side in the lower drum, while in the upper drum only two elements 2 are lying side by side. Still it is possible to locate the total heating surface in the lower drum keeping the upper drum free from heating elements. Each individual heating element comprises an inlet header 2' resp. 4', an outlet header 2" resp. 4" and bent tubes connecting both headers. The steam flows to the inlet header from the fire heated coils of the closed circuit not shown in the drawings, through the pipe 5, and the condensate generated in the heating elements flows back from the outlet header through the pipe 6 to the heated coils. This construction of the closed circuit is known and need not be further explained here.

In the upper drum there is an adjustable water level, offering a relatively large steaming surface. The water spaces of the two drums 1 and 3 are connected by pipes 9. At the crown of the lower drum 3 steam pipes are connected, opening into the steam space 70 of drum 1. Above the outlet of these pipes 10 a baffle plate 11 is arranged in order to separate the water entrained from the lower drum by the flow of steam. The steam coming from the lower drum mixes with the 75 steam generated in the upper drum. Steam is drawn off by the steam valve 12. In the steam space of the upper drum dripping plates are arranged, by means of which the feed water entering through the pipes 14 is 80 preheated and deaerated. From the dripping plates the feed water is led to the bottom of the lower drum by pipes 15. The upper drum is not fed directly; feed water is supplied to the upper drum from the lower drum 85 90 by the pipes 9.

As, according to the invention, the greater portion of the heating surface or, as the case may be, the whole heating surface is located in the lower drum, this lower drum being constantly filled with water, the heating surface will be permanently covered by water even in case there are very high fluctuations of the water level in the upper drum. The heating surface in the upper drum being compar- 95 100

atively small, if existent at all, is of little importance for the generation of the total amount of steam. Therefore it is possible to allow the greatest fluctuations of the water level in the upper drum without impairing the output of the boiler in a noticeable degree.

A further advantage of the boiler is that water in the lower drum is continually in a most lively motion, owing to the large heating surface contained in this drum. Steam generation is very vivacious and the impurities precipitated are entrained with the steam to the crown of the drum, where steam is taken off to the upper drum. The steam flowing to the upper drum entrains great quantities of fluid and impurities to the upper drum, as has been shown by tests. In the upper drum the water is comparatively quiet. Therefore impurities can deposit here. By these means a substantial advantage for the continuous working of the indirectly heated boiler is obtained, the lower drum remaining free from deposits and the transfer of heat not being impaired. Priming of water from the lower drum to the upper drum is not detrimental as the steam space in the upper drum can be so large that the steam drawn off will be dry with certainty in any case.

Having described my invention, what I claim as new and desire to secure by Letters Patent of the United States is as follows:—

1. In a steam generating plant indirectly heated by a circulating heat carrier two boiler drums one being situated on a higher level than the other, pipes connecting the water spaces of the two drums, an adjustable water level only in the upper drum, pipes leading from the upper part of the lower drum to the steam space of the upper drum and heating elements for heating the water contents of the drums, the major part of the heating elements lying in the lower drum.

2. In a steam generating plant indirectly heated by a circulating heat carrier two boiler drums one being situated on a higher level than the other, pipes connecting the water spaces of the two drums, an adjustable water level only in the upper drum, heating elements located in the lower drum and pipes leading from the upper part of the lower drum to the steam space of the upper drum.

3. In a steam generating plant as claimed in claim 1 dripping plates arranged in the steam space of the upper drum and feed water pipes leading to these dripping plates.

In testimony whereof, I have hereunto set my signature.

OTTO ENGLER.
